UNITED STATES PATENT OFFICE.

WILLIAM C. BOWLEN, OF GREENFIELD, MASSACHUSETTS, ASSIGNOR TO ROGERS, LUNT & BOWLEN COMPANY, OF GREENFIELD, MASSACHUSETTS, A CORPORATION OF MASSACHUSETTS.

DESIGN FOR A KNIFE.

42,041.

Specification for Design.

Patented Dec. 26, 1911.

Application filed May 5, 1911. Serial No. 625,416. Term of patent 3½ years.

To all whom it may concern:

Be it known that I, WILLIAM C. BOWLEN, a citizen of the United States of America, residing at Greenfield, in the county of Franklin and State of Massachusetts, have invented a new, original, and ornamental Design for a Knife, of which the following is a specification, reference being had to the accompanying drawing, forming a part thereof, in which—

Figure 1 represents a front elevation of a knife, showing my new design, and Fig. 2 is a corresponding side elevation of the handle part of the knife.

The knife consists of the handle and blade portions, the handle portion being substan-

tially octagonal in cross-section and tapering in opposite directions upon two of its opposite dimensions, the blade portion being laterally curved and provided with projections upon both edges thereof, the projection upon the cutting edge being nearer to the handle member than the projection upon the back edge of the knife blade.

I claim:

The ornamental design for a knife, as shown and described.

WILLIAM C. BOWLEN.

Witnesses:
